FLYING SHEAR

Robert H. Ellis, Pittsburgh, Pa., assignor to United
Engineering & Foundry Company, Pittsburgh,
Pa., a corporation of Pennsylvania

Application August 3, 1932, Serial No. 627,341

9 Claims. (Cl. 164—68)

This invention relates to flying shears or devices having similar operating characteristics, and more particularly to a control system for governing the operation of such apparatus.

5 The primary object of the invention generally stated is to provide a control system of novel form which is adapted to automatically regulate the operation of a flying shear in such a fashion as to determine the length of the first, or cropping, cut made by the shear, as well as the lengths of the subsequent or regular cuts.

Another object is to provide a system of this character which may be easily and readily adjusted to vary the lengths of the cuts anywhere 15 from substantially zero up to the full length of the stock being operated upon, without necessitating any mechanical adjustment of the shear or the means employed to feed the stock into the shear.

20 A further object is to provide in such a system for automatically compensating for any variations in the speed of the stock which may be caused by variations in the speed of the feeding mechanism in such a way that such variations 25 will not vary the lengths of the cuts.

A still further object is to provide for controlling the operation of a flying shear in such a way that the shear may be caused to produce cuts of any desired length, and its cutting blades so governed as to have a peripheral speed corresponding 30 to the linear speed of the stock being severed at the instant of cutting, irrespective of the speed of the stock.

These and various other objects, as well as the 35 various other novel features and advantages of the invention, will be apparent from the following detailed description when read in conjunction with the accompanying drawing, of which Fig. 1 is a diagrammatic illustration of a control 40 system comprising a single embodiment of the invention; Fig. 2 a diagrammatic side view of the shear and rolling mill shown in Fig. 1; and Fig. 3 an end view of the controller shown in Fig. 1, coupled to the motor employed for driving the 45 shear.

Referring to the drawing, the numeral 1 designates generally a rotary drum type flying shear which is coupled to a driving motor 2 and arranged to operate upon pieces of stock delivered 50 to it from a rolling mill 3 or other feeding device over a conveyor table 4. In this embodiment of the invention shear 1 is of the type known in the art as a start and stop shear being adapted to perform a single cut each time it is operated.

55 For effecting its operation motor 2 is connected

in a circuit comprising conductors 5 and 6 which furnish it with current supplied by a pair of line conductors M and N. In this circuit there is provided a circuit breaker 7 for controlling the current supply to motor 2. For in turn controlling the operation of this circuit breaker a drum type controller 8 is provided, which is coupled directly to the drive shaft of the motor 2. Upon the drum 10 of this controller there is provided a continuous conductor band 9 and an interrupted conductor band 11 which are connected together by a connector 12. Cooperating with these conductor bands are a pair of brushes 14 and 15 which are supported by a yoke 13 pivotally mounted on the axis of the controller. One 70 of these brushes 14 is connected to line conductor M and the other to the operating coil 7a of circuit breaker 7. From coil 7a this circuit is traced by way of a conductor 18 and a conductor 19 through a controller 17 to line conductor N. The 75 latter controller 17, which is also a rotary type controller, the details of which will presently be described, is adapted to complete the circuit through coil 7a momentarily each time it is rotated, and each time such circuit is completed 80 the circuit breaker 7 is closed and the shear motor 2 set in operation.

To maintain the motor 2 energized for a sufficient period for it to complete a cycle of operation each time it is set in motion, a holding circuit 21 is provided for the actuation coil 7a of the circuit breaker 7, which is traced from conductor 18 through an auxiliary bridging member 7b on breaker 7 to conductor 19 in shunt circuit relation with controller 17. With this arrangement, each time the shear motor is started by the closing of circuit breaker 7 in response to the operation of controller 17 it is maintained energized until the brush 15 of controller 8 runs off band 11 of drum 10. When this occurs the 95 breaker falls open and the motor stops, remaining out of service thereafter until the circuit breaker is again closed by controller 17.

In order that controller 8 will be in a position to operate and maintain the circuit for motor 2 until the shear has completed the cycle of operation each time circuit breaker 7 is closed, the interrupted conductor band 11 on its control drum 10 is so designed that the momentum of the shear and motor will move the controller sufficiently after breaker 7 is deenergized to re-engage band 11 with brush 15. While to adapt the shear to start from a preselected position of rest each time it is operated, a magnetic brake 22 is mounted on its drive shaft 23. For controlling 110

this brake its actuating coil (not shown) is connected to conductors 5 and 6 on the same side of breaker 7 as motor 2 by a pair of conductors 24 and 25. Thus, when the circuit breaker 7 is open brake 22 is placed in operation to bring the motor to rest, and as the characteristics of the motor 2 and brake are substantially constant under all conditions of operation, the shear is brought to rest in substantially the same over-travel after each operation.

To vary the time elapsing between the time when the shear is set in motion and the time when the blades of the shear move into cutting opposition to perform a cut, yoke 13, carrying the brushes 14 and 15 on controller 8, is mounted for circumferential adjustment about the drum 10. To effect this adjustment a lever 25, is secured to the yoke 13 and provided with a releasable latch 26 which is arranged to engage, a geared semi-circular race 57 rigidly mounted on the end of the frame in which the controller rotates (see Fig. 3). Another purpose of this adjusting feature of the controller, and the brake 22 employed on the shear motor, is to make it possible to vary the speed of the shear blades at the instant of cutting. This is done by setting the brake and controller in such positions that the shear motor will not have time to pick up full speed before the cut is made. Consequently, by varying the time between the starting of motor 2 and the time of cut the speed of the blades at the instant of cutting may be varied by such adjustment. The speed of the blades may be further varied, of course, by the use of a variable resistance 20 provided in the shear motor circuit.

Referring to controller 17, as illustrated, the drum 27 of this controller is provided with a continuous conductor band 28 and a conductor segment 29 which are connected together by a connector 31. Cooperating with these is a pair of brushes 32 and 33, respectively, which are mounted on a support 30 and connected to conductors 18 and 19 in the circuit through the actuating coil 7a of circuit breaker 7, previously traced. With this arrangement the circuit is completed through conductors 18 and 19 each time the conductor segment 29 makes contact with its associated brush 32. Hence, the shear is set in motion, as stated above, each time controller 17 is rotated, and consequently the length of the cuts made by the shear are determined by the speed at which the drum 27 is operated.

For driving controller 17 it is connected to a variable speed motor 34 through a magnetic clutch 35, the purpose of which latter will presently appear. The current for this motor is supplied to its armature, not shown, by conductors 36 and 37 which are connected to line conductors M and N through a variable resistor 38. This resistor is employed to vary the speed of motor 34 to in turn vary the speed of drum 27, and hence the lengths of the cuts made by the shear. It will be appreciated that the number of conductor segments 29 on the drum 27 may be varied, as well as the construction of the controller.

To further control the operation of the shear so that variations in the speed of the mill 3, or whatever other feeding means is employed, will not vary the lengths of the cut, the field windings of motor 34 (not shown) are connected by conductors 39 and 41 to the armature (not shown) of a generator 42 which is coupled to a motor 43 utilized to drive the mill. With this arrange-

ment, whenever the speed of the mill varies the output of generator 42 will vary accordingly and correspondingly the field current of motor 34, which will result in a corresponding variation in the speed of motor 34 and controller 17, which will compensate in the operation of the shear for the variations in the speed to the stock and maintain the lengths of the cuts constant.

As shown, motor 43 may be connected to line conductors M and N by means of conductors 44 and 45, and the field windings (not shown) of generator 42 by conductors 46 and 47 through a variable resistor 48. This latter resistor is provided primarily for varying the output of the generator 42 so as to provide the necessary current for the field of motor 34. However, as will be appreciated, it may also be utilized for varying the speed of the latter motor in somewhat the same fashion as resistor 38.

To provide for automatically controlling the length of the first cut made by the shear upon each piece of stock passed through it, or in other words to provide for cropping cuts, a flag switch 51 is mounted in the path of travel of the stock and is connected in a circuit 52 which is traced from line conductor M to line conductor N through the actuating coil 53a of a circuit breaker 53. This circuit breaker in turn is included in a circuit 56 traced from line conductor M to line conductor N through the magnetic clutch 35 connecting the controller 17 to its operating motor 34 and a magnetically operated stop 54 mounted on the shaft 55 of controller 17. The purpose of the clutch 35 is to permit the drum 27 of controller 17 being disconnected from motor 34 whenever the flag switch 51 is not engaged by a piece of stock, while the stop 54 is adapted to stop the drum 27 in a definite position each time the clutch 35 is released. This is for placing the drum in such a position for starting that the engagement of the front end of the stock with the flag switch will determine the first length of the cut. Obviously with such an arrangement the length of the first cut may be determined by the setting of stop 54, which may be adjustable. The details of construction of such a stop have been omitted, as well as those of the flag switch, inasmuch as such devices are so common in the art that it is not deemed necessary.

For operation the brushes on controller 8 are first adjusted so that the shear blades will have the proper cutting speed at the instant of cutting for the speed at which the strip is to be delivered to the shear, and the flag switch 51, which is adjustable, is so positioned, as is the mechanical stop 54, on the drum 27 of controller 17 that the length of the first cut will be determined. The motor 34 is then adjusted to give the proper speed to controller 17 to produce the lengths of cuts desired. With these adjustments made, when a piece of strip strikes the flag 51, circuit breaker 53 is energized which in turn releases the stop 54 of controller 17 and connects the drum 27 thereof to the motor 34 through the operation of the magnetic clutch 35 which is also energized by the closing of the circuit breaker 53. Thus, the drum 27 is set in motion to complete a circuit through the actuating coil 7a of the circuit breaker 7 as soon as the conductor segment 29 engages its cooperating brush 32.

With the closing of the circuit breaker 7 the holding circuit 21 is established by the closing of bridging members 7b and motor 2 is started. At the same time brake 22 is released and con-

troller 8 set in motion. Motor 2 once started continues to rotate until the conductor band 11 of controller 8 passes out of engagement with its cooperating brush 15. When this latter occurs the circuit through the actuating coil 7a of circuit breaker 7 is interrupted and the circuit breaker falls open deenergizing motor 2. At the same time the magnetic brake 22 operates bringing the shear and motor to rest. During such period of operation a cut is made and the shear is returned to its starting position. Thereafter, each time the conductor segment 29 on drum 27 engages its associated brush 32, a similar cycle of operation is repeated and such continues as long as the flag switch 51 is maintained closed by the stock. As soon as the trailing end of the stock passes out of engagement with flag 51, circuit 52 is broken and circuit breaker 53 allowed to open. With the opening of this circuit breaker the magnetic clutch 35 between the motor 34 and the controller 17 is deenergized, disconnecting the controller from such motor and at the same time mechanical stop 54 is rendered operative to stop the drum 27 in a preselected position of rest, where it is in readiness to control the length of the first cut when another piece of stock is fed into the shear.

As will be readily appreciated by those skilled in the art, the mechanical part comprising this system may take various other forms than those shown.

According to the provisions of the patent statutes, I have explained the principle and mode of operation of my invention and have illustrated and described what I now consider to represent its best embodiment. However, I desire to have it understood that, within the scope of the appended claims, the invention may be practiced otherwise than as specifically illustrated and described.

I claim:

1. A control system for a rotary flying shear comprising means for driving the shear, means for continuously feeding a piece of stock into the shear, means for automatically starting the shear at intermittent intervals, means for stopping the shear in a preselected position after each cut, and means responsive to the stock fed to the shear for placing said starting means in operation in such a manner as to produce a front end cropping cut of controlled length but which has no relation to the length of the subsequent regular cuts.

2. A control system for a motor driven flying shear comprising means for continuously feeding a piece of stock into the shear, means for automatically starting the shear motor in response to the stock in a manner to control the length of the first cut, means for automatically stopping said shear motor after each operation of the shear, and means for intermittently restarting the shear at regular predetermined intervals as long as said stock responsive means is engaged by the stock to produce uniform cuts the length of which has no relation to the length of the first cut.

3. A control system for a flying shear, comprising a motor for operating the shear, means for starting said motor at intermittent intervals, means for stopping said motor after each cut, and means for varying the speed of said motor starting means to vary the length of the cuts.

4. A control system for a flying shear, comprising a motor for operating the shear, means for continuously feeding stock into the shear, means for starting said motor at intermittent intervals,

means for stopping the motor after each operation of the shear and means responsive to said stock feeding means for varying the operation of said motor starting means in accordance with any variation which may occur in the speed of said feeding means.

5. A control system for a flying shear, comprising a motor for operating the shear, means for continuously feeding a piece of stock into the shear, means responsive to the stock for starting said motor in a manner to determine the length of the first cut, means for stopping the motor after each cutting operation of the shear, means for intermittently restarting said motor as long as said stock responsive means is engaged by the stock, variable speed means for driving said intermittently operable motor starting means to determine the length of the cuts, and means responsive to said stock feeding means for maintaining the operation of said motor restarting means synchronous with said stock feeding means.

6. A control system for a flying shear, comprising a motor for operating said shear, a source of current supply for said motor, a circuit breaker for controlling said motor, a controller coupled to said motor for controlling said circuit breaker, means operable in conjunction with said controller for closing said circuit breaker the controller being adapted to open the circuit breaker after each cutting operation of the shear, a magnetic brake for stopping said motor controlled by said circuit breaker, and means on said controller for varying the opening of said circuit breaker with respect to the cutting position of the shear.

7. A control system for a flying shear, comprising a motor for driving the shear, a source of current supply for said motor, a circuit breaker for controlling said motor, means for feeding a piece of stock into said shear, a flag switch arranged in the path of travel of the stock for closing said circuit breaker to control the first cut, a controller actuated by said motor for opening said circuit breaker after each cutting operation of the shear, a controller for restarting said motor, a second motor releasably coupled to said latter controller for effecting its actuation, and means responsive to said flag switch for connecting and disconnecting said second motor to the last-mentioned controller.

8. A control system for a flying shear, comprising a motor for driving the shear, a source of current for said motor, a circuit breaker for controlling said motor, a flag switch for closing said circuit breaker in response to the stock fed into the shear to control the length of the first cut, a controller coupled to said motor for automatically opening said circuit breaker at a preselected time after each cutting operation of the shear, a second controller for receiving said circuit breaker at intermittent intervals to determine the lengths of the cuts which the shear will make, a motor releasably connected to said latter controller, means responsive to said flag switch for connecting and disconnecting said second controller to its operating motor, means for feeding stock into the shear, and means responsive to said feeding means for varying the operation of said controller motor to maintain the lengths of the cuts constant.

9. A control system for a flying shear, comprising a motor for driving the shear, a source of current for operating and a magnetic brake for stopping said motor, a main circuit breaker for controlling said motor and motor brake, a rotary
